UNITED STATES PATENT OFFICE.

JOHN W. WILLEFORD, OF THOMASVILLE, GEORGIA.

WINDOW-SHADE-ROLLER HANGER.

1,233,007.

Specification of Letters Patent. Patented July 10, 1917.

Application filed December 29, 1916. Serial No. 139,606.

To all whom it may concern:

Be it known that I, JOHN W. WILLEFORD, a citizen of the United States, residing at Thomasville, in the county of Thomas, State 5 of Georgia, have invented a new and useful Window-Shade-Roller Hanger; and I do hereby declare the following to be a full, clear, and exact description of the invention, such as will enable others skilled in the art 10 to which it appertains to make and use the same.

This invention relates to a new and useful window shade roller hanger, and one of the objects of the invention is to provide 15 a hanger of this kind comprising simple, efficient and practical features of construction.

A further object of the invention is the provision of a hanger having means where- 20 by it may be adjusted to fit window frames of different sizes transversely.

A further object of the invention is to provide a hanger of this kind, to be so mounted, as to automatically assume a 25 proper horizontal position, or properly balanced, when the shade is lowered, after which the single screw may be tightened in order to hold the hanger in place.

A further object of the invention is to 30 provide an improved bracket for the shade roller provided with a gravity actuated latch, to hold the pintles of the shade roller in the bracket.

In practical fields, the details of construc- 35 tion may necessitate alterations falling within the scope of what is claimed.

The invention comprises further features and combination of parts, as hereinafter set forth, shown in the drawings and claimed.

40 In the drawings:

Figure 1 is a view in perspective of a portion of a window frame, showing the improved shade roller hanger applied, and constructed in accordance with the invention. 45

Fig. 2 is a sectional view on line 2—2 of Fig. 1, showing parts in section and parts in elevation.

Fig. 3 is a sectional view on line 3—3 of 50 Fig. 2.

Fig. 4 is a detail perspective view of one of the brackets carried by the hanger.

Referring more especially to the drawings, 1 designates a window frame which 55 may be any suitable construction or configuration, and 2 denotes the hanger. This

hanger comprises the two end sections 3 and 4 and the intermediate section 5, which, adjacent its ends, is provided with elongated slots 6. The inner face of the intermediate section is provided with a longitudinally extending groove 7, which is engaged by the elongated tongues 8 of the end sections 3 and 4. The end sections are provided with apertures 9, which have adjoining countersinks 10, which are adjacent the faces of the end sections which engage the frame of the window. Screw bolts 11 are provided, one to extend through any one of the apertures 9 of each series. Said bolts 11 pass through the elongated slots 6 of the intermediate section and are provided with nuts 12, which engage or enter the countersinks of the apertures that may receive said bolts. Between the heads of 75 the bolts and the outer face of the intermediate section, washers 13 are provided, to avoid wear on the intermediate section, as well as preventing the heads of the bolts from tending to pull through the slots. A 80 single screw 14 passes through the intermediate section at a point substantially equally between the ends of the intermediate section and also between the adjacent ends of the end sections, and into the window 85 frame. The screw 14 has a washer 15, which is positioned between the head of the screw and the outer face of the intermediate section.

Secured by the screws or the like 16, upon 90 the outer faces of the end sections, near their outer ends, are suitable brackets 17. The outwardly extending portions 18 of said brackets are provided with bifurcations 19, which cause the forks 20 and 21 to be formed. However, it will be noted that the crotch 22 of the bifurcation of one of said brackets is very narrow, in order to permit the insertion of the flat pintle 23, which is used to wind the spring (not shown) of the 100 shade roller 24. The crotch 25 of the bifurcation of the other bracket is semi-circular, and large enough to receive the cylindrical pintle 26 of the other end of the shade roller, which is provided with the usual shade 105 27. Pivots mounted upon the pins 28 of the forks 21 of both brackets, are latch members 29. Each latch member is U-shaped in cross section, as shown, and arches over the fork 21. It is to be noted that the pivot pins 28 are nearer the outer ends of 110 said latch members than their inner ends, so

that the inner ends (the side flanges of which overlie the bifurcations adjacent their crotches) of said latches will fall in the path of the pintles 23 and 26, to hold them 5 in place. The lower edges of the side flanges of the latches are inclined, as shown in Fig. 4 clearly, whereby, when inserting the shade roller, the pintles will cam against said edges and lift the inner ends of said 10 latches, whereby the inner ends of the latches, when the pintles reach the crotches, will fall in the path of said pintles by gravitation, thereby holding the shade roller in place. When hanging the shade and its 15 roller, the roller is mounted in the brackets, after which the three sections of the hanger are arranged, so that the inner ends of the sections 3 and 4 will be spaced equal distances upon each side of the pivot screw 14. 20 After so arranging said sections, the hanger is mounted upon the window frame and the single screw 14. The shade is then pulled down to the required distance, in which case the hanger will balance on the single screw, 25 so that the opposite edges of the shade are in parallelism with the sides of the window frame, after which the screw is tightened, holding the shade securely.

The invention having been set forth, what 30 is claimed as new and useful is:—

In a shade roller hanger, a pair of outer end hanger sections provided upon their

outer faces with longitudinally extending ribs, and their inner faces for their full lengths adapted to engage flat against the 35 outer face of the upper rail of a window frame, an intermediate elongated hanger section provided with elongated slots adjacent its ends and a longitudinally extending groove on its inner face to receive the ribs 40 of the outer end hanger sections, whereby said end sections may be slidably adjusted, means passing through the elongated slots and having adjustable connections with said end sections, whereby said end sections may 45 be held in adjusted positions, brackets carried by the outer ends of the end sections and provided with means for detachably holding the pintles of a shade roller, and a screw passing through the center of the intermediate section and between the adjacent inner ends of the end sections and threaded into the upper rail of a window frame, whereby the hanger may assume an equally balanced horizontal position, after which 50 said screw may be tightened.

In testimony whereof I have signed my name to this specification in the presence of two subscribing witnesses.

JOHN W. WILLEFORD.
